CENTER-PUNCH.

SPECIFICATION forming part of Letters Patent No. 781,947, dated February 7, 1905.

Application filed July 15, 1904. Serial No. 216,697.

To all whom it may concern:

Be it known that we, JAMES J. HARTLEY and JOSEPH M. STRYHAL, citizens of the United States, residing at Schenectady, in the county of Schenectady and State of New York, have invented a new and useful Improvement in Center-Punches, of which the following is a specification.

This invention has reference to an improvement in punches, and more particularly to an improvement in automatic centering or prick punches for machinists' use.

The object of our invention is to improve the construction of an automatic centering or prick punch whereby the construction is simplified and the cost of manufacture is reduced.

Our invention consists in the peculiar and novel construction of an automatic centering or prick punch having a hollow cylindrical handle, a spring-actuated plunger or hammer in the handle, a tubular tip secured by screwing it into the open end of the handle, a spring-pressed pointed punch-rod in the tubular tip having a cap in which is an offset aperture, a thimble having a hole forming an inwardly-extending circular lip in its top placed intermediate the plunger and the tubular tip, forming a stop for the plunger, and a pawl pivotally secured to the plunger under spring tension adapted to enter the offset aperture in the cap on the punch-rod, said pawl having a beveled tooth adapted to engage with the edge of the offset aperture to hold the plunger when depressing the handle and to engage with the inwardly-extending tip on the thimble to release the plunger which, actuated by a coiled spring, strikes the upper end of the punch-rod and drives the pointed end into the article to be centered or indented, with other details of construction, as will be more fully set forth hereinafter.

Figure 1 is a side view of our improved automatic centering-punch, showing the handle broken away to more clearly show the construction of the punch. Fig. 2 is a sectional view taken lengthwise through the punch, showing the punch in its normal position in full lines and in the position it would assume

by depressing the handle to the point of releasing the plunger to strike the blow in broken lines. Fig. 3 is a side view of the plunger removed from the handle, showing the means of pivotally securing the pawl to the plunger under spring tension. Fig. 4 is a vertical sectional view of the stop-and-pawl-releasing thimble. Fig. 5 is a side view of the tubular tip and pointed punch-rod removed from the handle, showing the cap on the upper end of the punch-rod broken away to clearly show the offset aperture in the cap. Fig. 6 is a top view of the stop-and-pawl-releasing thimble, showing the inwardly-extending circular lip for releasing the pawl; and Fig. 7 is an upper end view of the tubular tip, cap, and punch-rod, showing the offset aperture in the cap of the pawl.

In the drawings, *a* indicates a hollow cylindrical handle having the closed end *a'*, the internal screw-threaded open end *a''*, and the cylindrical bore *a''*, stepped to form the shoulder *a'*, as shown in Fig. 2. A tubular tip *b*, having the longitudinal hole *b'*, stepped to form the shoulder *b''*, is secured by screwing the screw-threaded end *b''* into the internal screw-threaded end *a''* of the handle. A punch-rod *c*, having the pointed end *c'*, and the reduced portion *c''*, forming the shoulder *c''*, extends upward through the hole *b'* in the tip. A coiled spring *c'* surrounds the reduced portion and abuts on the shoulder *c''* and the washer *c''*. A cap *c''*, having the offset aperture *c''*, is secured by screwing it onto the protruding upper end *c''* of the punch-rod *c* over the washer *c''*, as shown in Fig. 2. A stop-and-pawl-releasing thimble *d*, consisting of a cylindrical shell having the inwardly-extending circular lip *d'* in its top, is held in the cylindrical bore *a''* of the handle intermediate the washer *c''* and the shoulder *a'*, as shown in Fig. 2. A cylindrical plunger *e*, having the recess *e'* cut out of the side of the plunger to form a lip, which in turn is cut through the center to form the oppositely-disposed lugs *e''* *e''*, as shown in Figs. 2 and 3, is adapted to have a sliding fit in the bore *a''* of the handle. A flat metal pawl *f*, having the beveled tooth

f' , the downwardly-extending ends f^2 f^3 , adapted to enter the offset aperture c^7 in the cap c^6 , and adjacent the upper end f^3 the notches f^4 f^5 , shaped to loosely fit the lugs c^2 c^3 on the plunger, is pivotally held in position on the plunger by the flat spring g , secured to the plunger by the screw g' . The free end of the spring g , bearing on the upper end f^3 of the pawl, holds the pawl in its normal position under spring tension, as shown in Figs. 2 and 3. A heavy coiled spring h is placed intermediate the top of the plunger e and the closed end a' of the handle a , as shown in Fig. 2.

15 When the operative parts of our improved automatic centering-punch are in their normal positions, the thimble d forms a stop for the plunger e and holds the washer c^5 between the lower end of the thimble and the upper end 20 of the tubular tip b . The pawl f extends downward through the thimble d and into the offset aperture c^7 in the cap c^6 , with the beveled tooth f' on the pawl engaging with the upper outer edge of the aperture c^7 in the cap.

25 In the operation of our improved automatic centering-punch the operator places the point c' in position on the article to be centered or indented and depresses the handle a by pushing down on the handle. The plunger e is held 30 by the pawl f , the coiled spring c^4 is compressed between the shoulder c^3 on the punch-rod c and the washer c^5 , and the spring h is compressed between the top of the plunger e and the closed end a' of the handle. When 35 the handle is depressed to the position as shown in broken lines in Fig. 2, the beveled tooth f' on the pawl engages with the inwardly-extending lip d' on the thimble d , which acting on the beveled tooth disengages the tooth f' on the pawl from the edge of the aperture c^7 in the cap c^6 . The plunger e now descends under the impulse of the coiled spring h and strikes a blow on the protruding upper end c^8 40 of the punch-rod, forcing the point c' of the punch-rod into the article to be centered or indented. As the plunger e descends to strike the blow the pawl f passes through the offset aperture c^7 in the cap c^6 . When the pressure on the handle is released, the plunger e 45 comes to a stop on the thimble d , the handle rises to its normal position by the tension of the coiled c^4 , and the pawl f , acting un-

der the tension of the spring g , moves outward to bring the tooth f' on the pawl into engagement with the upper outer edge of the aperture c^7 in the cap c^6 when the handle has reached its upward limit and brought the cap c^6 into its normal position, as shown in Fig. 2.

Having thus described our invention, we claim as new and desire to secure by Letters Patent

1. An automatic center-punch having a hollow cylindrical handle closed at one end, a tubular tip secured to the open end of the handle, a spring-pressed punch-rod in the tubular tip, 65 a spring-actuated plunger in the handle, a pawl pivotally secured to the plunger under spring tension, a tooth on the pawl, a cap on the upper end of the punch-rod in which is an offset aperture, and a thimble having an inwardly-extending lip adapted to form a stop for the plunger and to release the pawl, as described.

2. In an automatic center-punch, the combination of a hollow cylindrical handle closed at one end, a tubular tip secured to the open end of the handle, a shouldered punch-rod in the tubular tip, a washer on the upper end of the tubular tip, a coiled spring on the punch-rod intermediate the shoulder and the washer, 75 a cap having an offset aperture secured to the upper end of the punch-rod, a thimble having an inwardly-extending lip in the handle, a cylindrical plunger in the handle, a pawl having a beveled tooth pivotally secured under spring tension to the plunger, and a coiled spring intermediate the plunger and the closed end of the handle, as described.

3. In an automatic center-punch, the combination of a hollow cylindrical handle a , a tubular tip b , a punch-rod c , a coiled spring c^4 , 90 a washer c^5 , a cap c^6 , a stop-and-pawl-releasing thimble d , a cylindrical plunger e , a flat metal pawl f , a flat spring g , and a coiled spring h , all constructed and for the purpose as described.

In testimony whereof we have hereunto signed our names to this specification in the presence of two subscribing witnesses.

JAMES J. HARTLEY.
JOSEPH M. STRYHAL.
